UNITED STATES PATENT OFFICE

115,431

DESIGN FOR AN EMBLEM LAMP

Thomas C. Surles, Beverly, Mass.

Substitute for abandoned application Serial No.
70,352, July 10, 1937. This application May 19,
1939, Serial No. 85,090

Term of patent 3½ years

To all whom it may concern:

Be it known that I, Thomas C. Surles, a citizen of the United States, residing in Beverly, in the county of Essex and Commonwealth of Massachusetts, have invented a new, original, and ornamental Design for an Emblem Lamp, of which the following is a specification, reference being had to the accompanying drawing, forming a part thereof, in which:

Fig. 1 is a view in elevation of an emblem lamp showing my new design,

Fig. 2 is a view of the lamp in side elevation with the back of the lamp shown conventionally in broken lines.

This application is a substitute for my previous application Serial No. D. 70,352 filed July 10, 1937.

I claim,

The ornamental design for an emblem lamp, substantially as shown and described.

THOMAS C. SURLES.
